UNITED STATES PATENT OFFICE.

HENRY SELLING, OF NEW YORK, N. Y., ASSIGNOR TO H. SELLING & CO., OF SAME PLACE.

DESIGN FOR A FABRIC.

SPECIFICATION forming part of Design No. 13,200, dated August 15, 1882.

Application filed July 19, 1882. Term of patent 3½ years.

To all whom it may concern:

Be it known that I, HENRY SELLING, a citizen of the United States, residing at New York, in the county of New York and State of New York, have invented and produced a new and original Design for Fabrics of all Descriptions, of which the following is a specification, reference being had to the accompanying illustration, forming part thereof.

10 The leading feature of my design consists in the peculiar arrangement of a series of figures or illustrations produced in any desired manner upon the surface or in the body of any suitable fabric, representing the various stages 15 of development of the cultivated "chandron" or artichoke plant from the time of sprouting until maturity, or the formation of the nut or seed. These figures or illustrations are arranged in symmetrical groups, representing 20 the lower stages of development of the plant at the lower part of the illustration, and the succeeding stages of development as the illustrations proceed upward, the final stage being

indicated by the plant fully matured. The design as thus produced is repeated throughout 25 the length of the fabric.

The design is to be applied to all descriptions of fabric and to be produced in any desirable manner; but it is intended especially to be formed in raised or depressed figures by 30 embossing, stamping, printing, or otherwise upon plush, velvet, or other material, and on wall-paper, and other fabrics to be employed as furniture-coverings, coffin-coverings, for articles of wearing-apparel, and for domestic 35 and other purposes too numerous to mention.

I claim—

A design for fabrics, consisting of a representation of the chandron or artichoke plant, illustrating the different stages of development of the same in a series of figures grouped substantially as specified.

HENRY SELLING.
